UNITED STATES PATENT OFFICE.

NETTIE LINTON, OF ALLABEN, NEW YORK.

DEVICE FOR PRODUCING STAGE-RAIN.

1,106,391.

Specification of Letters Patent. Patented Aug. 11, 1914.

Application filed March 25, 1912. Serial No. 686,055.

To all whom it may concern:

Be it known that I, NETTIE LINTON, residing at Allaben, in the county of Ulster and State of New York, have invented new and useful Improvements in Devices for Producing Stage-Rain, of which the following is a specification.

My invention which will be hereinafter fully set forth and claimed relates to stage effects and particularly to devices for producing the optical effect of rain, for stage purposes and the like.

The object of my invention is a device for producing with simple and inexpensive means the optical effect or illusion of rain.

In the drawings, which will be understood to be more or less diagrammatic;—Figure 1 is an elevation of the interior of a window, fitted with my device. Fig. 2 shows the same window on the exterior and disclosing more of the means of producing the effect. Fig. 3 may be regarded as a plan or transverse (horizontal) section of the same on line 3, 3, Figs. 1 and 2. Fig. 4 is a vertical section of the same on line 4, 4, and Fig. 5 is a detail in perspective on a larger scale, showing a manner of suspending a part of the device.

In the drawing, my device is applied to the limited space of a window, for the sake of compactness, but it will be understood that it is applicable to more extended scenes and in fact to scenes stretching entirely across the stage.

W is a window formed in a scene piece S and fitted with blind, B, and curtains, C; the latter on a pole, c, and caught in the lower ends in loops c¹. These parts are non-essential in my device and merely shown for the sake of completeness of the display and Fig. 1 represents the same as seen from the auditorium, while Fig. 2 is a view as seen from the rear or stage side.

The space behind which the rain effect is to appear, being in this case the space of the window W which is usually supposed to be glazed, is covered with gauze, denoted in the drawing by the letter G and upon which, in the present instance, the bars c² (Figs. 1 and 2) are secured. Silk gauze has proved to be particularly well suited for certain effects, but other gauzes may be used.

At the rear and above the soffit of the window, conveniently on a rail, 2, forming part of the scene piece S, Fig. 2, are secured a pair of brackets, 3, adapted to swivel

horizontally on their support, and from these are suspended, at some little distance from the gauze, by light springs, 4, a rod, 5, to which the springs are fastened. Fig. 5 shows the arrangement in detail. The rod 5 carries a number of rings, 6, secured to a cord, 7, from which are suspended, in the form of a curtain, a series of cords, strings or bands, 8, of a glittering character—ordinary tinsel has been found to answer the purpose very well. One end-ring, marked 6¹ for the sake of distinction, is secured to be stationary in its place and thus prevented from sliding on the rod 5, as the other rings are free to do, like ordinary rings on a curtain pole. The other end-ring has two cords or strings, 9, and 10, secured to it, one passed through a stationary eye, such as the eye on the end of the rod 5, and has its end suspended to be operated by hand (Fig. 2) or otherwise, and the other, 9, is passed through all the other rings and its end suspended. This latter serves to draw all the rings to one end and thus clear the window from the strings 8 when the operation of the device is not desired. The cord 10 serves also to give a vibratory motion to the rod 5, the cord 7 and the strings, 8, such motion being aided by the springs 4.

A strong light is thrown from a reflector lamp, L, Fig. 2, between the gauze G and the curtain of strings 8, so that its main effect is on the latter. Rays of light are indicated at L^r in Figs. 2 and 3. The strings 8 being light and thus assuming a more or less undulatory vertical line, give broken reflections from their glittering parts when the light is thrown on them and a slight vibratory motion given to them by means of the cord 10, which imitates torrents of rain with great realistic effect when seen through the gauze G.

It will be seen that no water whatsoever is used, the effect being produced by gauze, glittering strings, light-reflections and a vibratory movement of the strings.

I claim as my invention:—

1. In a stage effect for rain, the combination of a scene piece having an opening in it formed for a window, silk gauze covering said opening and having window bars formed on it, a curtain formed of strings of tinsel suspended at one end at the rear of said gauze and some distance from it, a cord from which said strings of tinsel depend, rings secured to said cord, a curtain rod

upon which said rings are strung, a spring at each end of and supporting said rod, a bracket secured to the scene piece at each end of said rod and supporting said springs, 5 cords secured to one end-ring by means of which the rings may be moved along the rod and a vibratory motion given to the curtain and a lamp throwing light upon the front of the curtain from the rear of the 10 gauze, substantially as set forth.

2. In a stage effect for rain, a window having the opening covered with gauze, a curtain formed of suspended strings of tinsel at the rear and a little distance from the 15 gauze, means of opening and closing said curtain, means of giving a vibratory motion to said curtain and means of throwing light-reflections onto the front of said curtain but from the rear of the gauze, substantially as 20 set forth.

3. In a stage effect for rain, the combination of a surface formed of gauze covering the opening forming the view, a curtain rod at the rear of the gauze and above the soffit 25 of the opening, springs on which said rod is

suspended, brackets supporting said springs, a series of rings on said curtain pole, a cord supported by said rings and a series of strings of glittering material suspended at their upper ends from said cord and cords 30 for opening and closing said curtain of strings and giving a vibratory motion to the same, substantially as set forth.

4. In a stage effect for rain, the combination of a surface of gauze covering an opening forming the view, a curtain formed of depending strings of glittering material suspended at the rear of the gauze, means for throwing light-reflections on the front of 35 said curtain from the rear of the gauze and 40 means of giving a vibratory motion to said curtain, substantially as set forth.

In testimony whereof I affixed my signature, in presence of two subscribing witnesses.

NETTIE LINTON.
